UNITED STATES PATENT OFFICE.

LINA MATTHEWS, OF ROSEWOOD, TEXAS.

PENHOLDER.

SPECIFICATION forming part of Letters Patent No. 788,413, dated April 25, 1905.

Application filed October 8, 1904. Serial No. 227,637.

To all whom it may concern:

Be it known that I, LINA MATTHEWS, a citizen of the United States of America, residing at Rosewood, in the county of Upshur and State of Texas, have invented a certain new and useful Penholder, of which the following is a specification, reference being had therein to the accompanying drawings.

This invention relates to penholders of the type embodying means for facilitating the extraction of a pen-point without the necessity of handling the same, thereby preventing the soiling of the fingers.

To this end the invention contemplates a simple and practical form of penholder attachment for penholders which comprises simple and effectual means for releasing and ejecting a pen-point without handling the same while at the same time providing for firmly holding the pen-point in place and also for maintaining a firm seating of the spring member in such way as to prevent displacing the latter and also to assist in maintaining the pen-bearing section upon the handle stem or stock.

With these and other objects in view, the nature of which will more fully appear as the description proceeds, the invention consists in the novel construction, combination, and arrangement of parts, as herein fully described, illustrated, and claimed.

The essential feature of the invention residing in the construction for carrying out the object above indicated is susceptible to some structural change without departing from the scope of the invention; but the preferred embodiment of the latter is shown in the accompanying drawings, in which—

Figure 1 is a perspective view of a penholder embodying a spring-holding attachment for the pen-point, said attachment being constructed in accordance with the present invention. Fig. 2 is an enlarged sectional view of the pen-bearing section of the penholder. Fig. 3 is a cross-sectional view on the line 3 3 of Fig. 2. Fig. 4 is a detail plan view of the detaining-spring and the pen-holding plate carried thereby.

Like reference-numerals designate corresponding parts in all the figures of the drawings.

In carrying out the present invention no change is involved in the conventional character of the penholder, which essentially consists of the usual handle stem or stock 1 and the tubular pen-bearing section 2, carried 55 thereby. The lower open end of the tube or sleeve constituting the pen-bearing section 2 is designed to receive the heel of the pen-point 3, while the opposite end of said pen-bearing section fits over the reduced supporting-neck 60 4, formed at one end of the stem or stock 1. The said reduced supporting-neck 4 is flattened at one side, as indicated at 5, to receive in the interval between the same and the inner wall of the pen-bearing section 2 the inner 65 end of a compoundly-bowed retaining-spring 6. This retaining-spring is preferably of a flattened form and is arranged longitudinally within the pen-bearing section. The outer end portion of the spring carries a concavo-convex widened pen-holding plate 7, conforming in curvature to the lower end portion of the tube or section 2, accommodating between the same and said tube or section the pen-point 3, as plainly shown in Fig. 2 in the 70 drawings.

The pen-holding plate 7 may be an integral part of the spring 6 or separately fastened thereto, so as to be rigid with the same, and at a distance above the lower or outer end of 80 the plate 7 the same has rigidly secured thereto the shank of a release-button 8, which projects through an opening 9 in the tube or section 2 and is exposed above the upper side of the latter for convenient manipulation by the 85 thumb or finger of the hand.

The bowing of the spring 6 between the release-button 8 and the neck 4 of the stem 1 provides for firmly seating the inner end of the spring over the flattened side 5 of the handle-stem, thereby firmly positioning the spring and maintaining the plate 7 accurately in position for holding the pen-point. At the same time a spring pressure is exerted between and against the pen-bearing section and the flattened side 5 of the handle-stem, thus serving to materially assist in retaining the pen-bearing section firmly upon the handle-stem.

When it is desired to release and eject the pen, it is simply necessary to press inwardly 100

upon the release-button 8. When the pressure of the finger is released from the button 8, the holding-plate normally lies in position for admitting a pen-point to be inserted in the 5 usual way.

Having thus described the invention, what is claimed as new, and desired to be secured by Letters Patent, is—

In a penholder, the combination of a handle-
10 stem provided with a flat spring-seat on its upper side, a tubular pen-bearing section fitting over said seat, and a flat bow-spring one end

of which fits with a spring-pressure between the seat and the pen-bearing section so as to frictionally connect said parts, and the other 15 end of which clasps the pen, both ends of the spring being disposed at the same side of the pen-bearing section.

In testimony whereof I affix my signature in presence of two witnesses.

LINA MATTHEWS
